ATTORNEY

UNITED STATES PATENT OFFICE.

NICHOLAS GREY, OF NEW BRUNSWICK, NEW JERSEY.

WINDOW-SCREEN.

1,264,638.

Specification of Letters Patent. Patented Apr. 30, 1918.

Application filed July 14, 1916. Serial No. 109,382.

To all whom it may concern:

Be it known that I, NICHOLAS GREY, a citizen of the United States, residing at New Brunswick, in the county of Middlesex and State of New Jersey, have invented certain new and useful Improvements in Window-Screens, of which the following is a specification.

This invention relates to window screens, and has for its primary object to provide improvements in that type of screens wherein a roll of open mesh fabric is employed, and which has one end fastened to the lower stile of a sliding sash, whereby the fabric will be rolled and unrolled as the window is lowered and raised.

A further object of the invention is to provide a screen of this character which is constructed and arranged in such manner as to be adaptable to windows varying in width, the construction preventing entrance of flies, mosquitoes and other insects to the room.

A still further object of the invention is to provide a screen device of this character which is capable of being readily attached to and detached from the sliding sash, and which operates to exert downward movement to the sash.

A still further and particular object of the invention is to provide a roll screen of the above described character, which is of simple and inexpensive construction, which is composed of but few readily assembled parts, all so constructed and arranged as to prevent wear, breakage or derangement of the same, which is proof against becoming disordered, which is positive in operation, and which will prove thoroughly efficient in the attainment of the ends for which it is designed.

With these objects in view, together with others which will appear as the description proceeds, the invention resides in the novel formation, combination and arrangement of parts, all as will be described more fully hereinafter, illustrated in the accompanying drawings, and distinctly pointed out in the claims.

The invention will be best understood by

reference to the accompanying drawings, wherein:

Figure 1 is an interior elevation of a conventional form of window frame and sashes, illustrating the application of a roller screen embodying my invention;

Fig. 2 is a vertical sectional view taken through the frame and sashes;

Fig. 3 is an enlarged longitudinal sectional view taken through the roller screen and housing therefor; and

Fig. 4 is a sectional view taken on line 4—4 of Fig. 3.

Referring now more particularly to the drawing, 5 indicates a window frame of the usual well known construction, having the sliding lower and upper sashes 6 and 7 respectively.

The housing for the roller screen is indicated generally at 8 and comprises a pair of telescopic tubular sections 9. Each of these sections is provided at one end with a head 10, in the form of an annular plate, having inwardly projecting perforated lugs or ears 11, which engage the inner periphery of the end of the adjacent tubular housing section, and through which suitable screws or rivets extend to secure the heads to said sections. It will be understood that the tubular sections 9 are of equal diameter with the heads 10, and each section is provided upon one side with an outwardly extending foot 12, by means of which the same may be secured to the sill of the window frame. The adjacent ends of the sections 9 forming the housing 8 snugly interfit, and are capable of sliding one within the other.

One side of each of the tubular members 9 is hinged at its lower end as at 13, the said hinged portion constituting a door, by means of which access to the interior of the housing may be readily had. The free end of the door portion of the housing when the said door is closed, is spaced from the adjacent end of the fixed portion, whereby a slot or opening 14, coextensive with the housing, is provided.

Each of the heads 10 is provided with a stem or rod 15, the said stems being secured to the heads at the central portions thereof, 100

- and extend inwardly and centrally of the housing. These stems are relatively short length, and each has rotatably mounted thereon, a telescopic tubular roll section 16.
- 5 The innermost extremities of these sections are telescoped as shown in Fig. 3 of the drawings, and a connecting pin or screw 17 may be inserted through registering apertures 18 in the said sections to maintain the 10 same against sliding relative to each other.

Encircling each of the stems 15 is a torsional spring 19, one end of which is engaged through a suitable aperture at the free end of the stem, while the opposite end is 15 secured to the adjacent tubular roll section 16.

The screen which is indicated at 20, is arranged in overlapping sections, one section being secured to each of the tubular roll sections 16. The extremity of the screen fabric of each width is attached or in any other preferred manner secured to the roll section 16, and is led therefrom out through the slot 14 in the housing 8, to be secured at its free 25 end to the lower stile or cross bar of the sliding sash 6. The outer extremity of the screen fabrics are edged with beadings or ribs 21. These ribs are preferably formed of relatively thin metallic plates, bent and 30 rebent upon themselves as shown in Fig. 2 to confine and firmly secure the fabric end to the same. Outwardly projecting perforated ears 22 are formed upon the said ribs, whereby the same may be secured to the 35 window sash, tacks or nails being employed for this purpose. These beadings are also bent or formed in such manner as to permit of telescopic connection with each other, whereby the width of the end of the screen 40 fabric may be extended or contracted when required.

The inner faces of the window frame are equipped with vertically extending guides 23, the same operating to maintain the fabric properly stretched across the window 45 and to prevent bulging of the same.

The winding power of the springs 19 within the housing is such as will be capable of rotating the drum formed of the tubular 50 sections 16 with sufficient force to draw the sash 6 downwardly to closed position, and to maintain the sash raised, a rack and pawl arrangement is provided. The rack is indicated at 25, and is secured to one of the vertical stiles of the sash, while the pawl, illustrated at 26, is secured to the window frame and is adapted to engage within the teeth of the rack. From this construction it is apparent that the pawl will operate to prevent 55 downward movement of the window when it is desired to retain the same open.

In practice, the sections 9 constituting the housing are slid apart until the heads 10 engage with the inner faces of the frame

sides. The said housing is then secured to the sill with its slot portion 14 in close proximity to the lower transverse bar or stile of the sash 6. The ends of the overlapping screening are then connected to the lower bar of the window sash, and the device is ready 70 for operation. As the window is raised, the screening fabric is drawn through the slot 14 and across the space left open by the raising of the window. The guide strips 23 at the frame sides prevent bulging of the screen 75 fabric and also prevent insects gaining access to the room around the edges of the screen. The window is maintained in open position by the rack and pawl means 25—26. Upon releasing the pawl 26, the sash, by 80 operation of the torsional springs 19, will wind the drum or roll sections 16 to spool the screen fabric, whereupon the window sash will be drawn to closed position.

It is obvious that minor changes in the 85 details of construction, combination and arrangement of parts may be made without departing from the spirit of the invention or exceeding the scope of the claims.

What is claimed is:—

1. In a device of the class described, a pair 90 of tubular telescopic sections, heads at the ends of said sections, stems projecting inwardly from said heads and centrally of said sections, drum sections each rotatably 95 mounted at one end upon one of said stems and being telescopic at their opposite ends, means for securing together said telescoped ends, a pair of springs, each secured at one of its ends to one of said stems, and at its 100 opposite end to the corresponding drum section, and fabrics secured to said drum sections.

2. In a device of the class described, a pair 105 of tubular telescoping sections hinged along corresponding longitudinal edges to a stationary support, said sections being of arcuate form in cross section, stationary head members at the opposite ends of said sections, stationary telescoping upstanding 110 front members opposite said sections, said upstanding front members coöperating with said sections to form a casing, stems projecting inwardly from said head members, drum sections rotatably mounted at one end upon 115 said stems and telescoping at their opposite ends, springs secured to said drum sections and said stems to resiliently retain said drum sections against rotation, and fabrics secured to said drum sections and adapted to be 120 withdrawn from said casing at a point between the first mentioned sections and said upstanding front members.

3. In a device of the class described, a casing 125 formed of upstanding adjustable front members, hinged adjustable arcuate members having free edges terminating a spaced distance from the upper edges of said upstand-

ing front members to provide a longitudinal slot at the front upper edge of said casing, head members for said casing, means for connecting said arcuate members with said 5 head members, stems projecting into said casing from said head members, connected drum sections mounted on said stems, fabrics secured to said drum sections and extended through the slot of said casing, means for

resiliently connecting said drum sections to 10 said stems, and means for securing together said drum sections in adjusted position.

In testimony whereof I affix my signature in presence of two witnesses.

NICHOLAS GREY.
